UNITED STATES PATENT OFFICE.

JACOB TANNER, OF RIDGEFIELD PARK, NEW JERSEY, ASSIGNOR TO CESARE CARTOLTO AND ALBERT FREI, OF WEST NEW YORK, NEW JERSEY.

DESIGN FOR A SPANISH SHAWL.

Application filed November 12, 1927. Serial No. 24,087. Term of patent 3½ years.

To all whom it may concern:

Be it known that I, JACOB TANNER, a citizen of the Republic of Switzerland, residing at Ridgefield Park, in the county of Bergen and State of New Jersey, have invented a new, original, and ornamental Design for Spanish Shawls, of which the following is a specification, reference being had to the accompanying drawing, forming part thereof.

The figure is a plan view of one corner of a Spanish shawl, showing my new design, the other three corners being repetitions of the corner shown.

I claim:

The ornamental design for a Spanish shawl, as shown and described.

JACOB TANNER.
